UNITED STATES PATENT OFFICE

2,550,390

METHOD FOR TREATING FUEL

Nicholas N. Stephanoff, Philadelphia, Pa., assignor, by mesne assignments, to C. H. Wheeler Manufacturing Company, a corporation of Pennsylvania

Application August 25, 1944, Serial No. 551,239

4 Claims. (Cl. 241—1)

1

This invention relates to a method and apparatus for treating solid fuels and then burning the same, the invention relating primarily to the grinding or disintegration of solid fuels to a very fine dust, which dust, preferably without deposition from a suspension in elastic fluid in which it is ground, is fed to the point of combustion.

The broad object of the invention is to effect the fine grinding or disintegration just mentioned under proper conditions for delivery of the product to a burner.

Another object of the invention is the provision of a suitable burner arrangement for effecting complete combustion of such fine fuel.

These, and other objects of the invention, particularly relating to details of method and apparatus, will be apparent from the following description read in conjunction with the accompanying drawings, in which:

Figure 1 is a diagrammatic elevation partly in section showing a complete unit for the pulverizing and burning of fuel;

Figure 2 is an enlarged axial section showing details of the burner of Figure 1;

Figure 3 is a similar view of a modified form of burner;

Figure 4 is an end view of the burner of Figure 3, looking toward the delivery end thereof;

Figure 5 is a vertical section taken through an alternative form of apparatus for effecting the grinding and explosive disintegration of a solid fuel;

Figure 6 is a horizontal section through the same taken on the plane, the trace of which is indicated at 6—6 in Figure 5; and

Figure 7 is an enlarged fragmentary view on the same plane showing the construction of a nozzle.

The invention is applicable to carbonaceous fuels of a great variety of types as, for example, anthracite and bituminous coals, anthracite and bituminous culm, river coal, lignite, brown coals, peat, wood, bagasse, wood chips, tan bark, cokes of various types, or the like. It is further applicable to materials which are hard when cold but which soften when heated such as pitches, bitumens, and asphalts which in the cold state may be treated as hereinafter described. In special processing even materials of oxidizable nature not generally classified as fuels may be treated and for present purposes may be regarded as fuels. For example if the major end of a grinding and oxidizing step is to provide a metallic oxide in fine state, the metal may be ground

2

to a fine state of subdivision and then oxidized (burnt) in a combustion chamber in order to make use of the generated heat. However, inasmuch as these materials are all handled similarly and the fuel of primary interest is coal, to simplify the following discussion, coal will be generally referred to with the understanding that the remarks are applicable to the other materials as well. In some specific particulars, as pointed out hereafter, certain of these substances may handle differently.

Referring first to Figure 1, there is illustrated at 2 a boiler in which the pulverized fuel is to be burned. This is, however, merely by way of illustration since the burning may be accomplished for a large variety of purposes, for example for the heating of stills or other chemical apparatus or even for the production of combustion gases for the operation of turbines or other engines. The invention is also adapted for the preparation of fuel for use in Diesel or other internal combustion engines.

A motor 4 is illustrated as driving both a blower 6 to provide a supply of combustion air and a crusher 10 adapted to reduce the fuel which may be contained, in lumps or large pieces, in the hopper 8 to a size suitable for introduction through the feed passage 12 into a grinding mill 14. The pieces so introduced need not be fine and, in fact, the mill is well adapted for the grinding of particles of fuel or sizes of the order of pea coal or stove coal.

The mill 14 is illustrated conventionally and may be of the type described in my Patents Nos. 2,237,091, dated April 1, 1941, or 2,325,080, dated July 27, 1943. As illustrated in these patents and, in particular, the latter which represents an improved form of this type of mill, the mill comprises an endless tube having a lower turn 40 in which grinding is effected by the action of high velocity elastic fluid jets introduced through nozzles 16. The remaining portion of the mill serves for the purpose of recirculating large particles for further grinding, these being retained in the mill by centrifugal action, whereas as very fine ground particles are carried out of the mill in suspension in a current of the elastic fluid through the passage 36. The nozzles 16 are fed, preferably with steam, through the connection 18, the supply of steam to which is under the control of a control panel 20 which may also serve for control of the rate of feed through the operation of the motor 4. In the event that the fuel is burned under a boiler, it is convenient to use steam under high pressure

from the boiler, as the elastic fluid, to effect the grinding. In other cases, however, steam from a separate source may be used, or, alternatively, air or even combustible gases under high pressure may be used for effecting the grinding.

Air from the blower 6 passes through the connections 22 and 24, the latter controlled by a valve 26, to a space 28 from which it is delivered about the burner indicated at 38. A branch 30 from the connection 22, controlled by a valve 32, serves to mix air with the suspension of the fuel to carry the same through the pipe 34 to the burner. This connection is desirable in the event that steam is used as a grinding agent to insure that there is a substantial amount of air carrying the particles in their approach to the burner.

The burner itself is illustrated in enlarged fashion in Figure 2. It comprises the tube 40 receiving the suspension of powdered fuel in steam and air, the tube 40 discharging the suspension through the annular space 42 inside an annular air chest 46 and outside a liquid fuel feeding assembly. A suspension of fuel of the type here considered and as described in greater detail hereafter is not generally directly combustible unless projected into a space having a very high temperature. For the purpose, therefore, of initiating combustion or, in some cases, for sustaining the combustion, it is necessary to feed additional fuel which may be oil or combustible gas into the combustion zone. The burner illustrated in Figures 1 and 2 is designed for feeding in this fashion oil. This oil is fed through a pipe 52 into a space 54 between a sleeve 60 and the walls of a passage 56. For the adjustment of the flow of oil, the sleeve 60 is threaded into a fixed member 61 and is adapted to be rotated through gearing 62 and 64 by a shaft 66. By the rotation of the sleeve 60 it will be advanced or retracted due to its threaded mounting, thereby adjusting the clearance at the annular outlet 68. To effect dispersion of the oil thus fed, nozzles 44 in the inner wall of the chest 46 are directed so as to project high velocity jets of air or steam into engagement with the issuing oil to effect its atomization into condition for substantially instantaneous combustion. For this purpose, the nozzles 44 are preferably directed so as to cut across, more or less tangentially, the annular sheet of oil which emerges from the nozzle, being directed in the same direction about the axis so as to produce a violent swirling action. At the same time it will be noted that these jets cut across the suspension emerging at 42 so as to pick up this dispersion and completely mix it with the oil in the process of atomization. Thus, the combustion of the oil will result in the production of intense temperatures sufficient to cause combustion of even relatively refractory (low grade) solid fuels which may be introduced. To further insure complete and rapid combustion, auxiliary air is introduced into the combustion zone through passage 56, being fed thereto through the connection 58, receiving air from a relatively low pressure source as, for example, the connection 22. The flow of air or steam through the nozzles 44 may be controlled by a valve 59 in the feeding connection 48 which connection is made to a source of high pressure air which may, for example, consist of an auxiliary compressor of small size since the volume of air here needed is relatively small.

Alternatively, the jets issuing from nozzles 44 may be steam jets in which case the chest 46 is supplied with steam at high pressure from the

boiler in which burning occurs, or from an auxiliary source. The major air for completion of the combustion proceeds from the plenum 28 through the annular space 70 between the burner and the boiler walls 72.

An alternative form of burner is illustrated in Figures 3 and 4. In this modification, the burner comprises a tube having a conical discharge and providing a passage 76 through which the suspension of powdered fuel is fed, the connection being to a passage such as 34 of the preceding modification. Within the passage 76 is located a tube 78 into which liquid or gaseous fuel is fed through the connection 80. The tube 78 terminates in a small opening 82 which may be adjustably restricted by a valve rod 84 threaded at 86 into a support 88 and arranged to be rotated by gearing indicated at 90 connected to a hand wheel 92. By the rotation of the rod 84 it will be moved longitudinally to serve to adjust the opening.

About the discharge end of the passage 74 is located a chest 94 for the reception of high pressure air or steam to be discharged through nozzles 96 in jets having the directions which will be evident from the construction lines in Figures 3 and 4; i. e., the jets are directed forwardly in a skew direction about the axis of the tube 78 so that they will pick up both the suspension passing through the passage 76 and the liquid or gaseous fuel, creating intense turbulence and mixing these various constituents to insure complete and rapid combustion. In the case of liquid fuel, the jets will serve for its fine atomization. As in the previous modification, auxiliary air for supporting combustion will enter about the passage 74.

Where liquid fuel is referred to in the foregoing, there is intended to be meant fuel which is generally liquid form but which may include, for example, oil carrying in suspension fine particles of coal or other solid fuel, being of the so-called colloidal fuel type. This fuel may be provided, for example, by mixing a certain amount of the finely ground solid fuel with oil or any carbonaceous material which will flow when heated, thereby to reduce to a very substantial extent the amount of oil or other fluent fuel which may be used for initiating or sustaining combustion.

The feeding of liquid or gaseous fuel may be reduced or interrupted entirely after the furnace reaches a sufficient temperature to insure combustion of the solid fuel in suspension without auxiliary aid. For example, in starting up a considerable amount of liquid or gaseous fuel may be used in order to achieve rapid rise of the temperature of the walls of the combustion chamber to a point where, by radiation, they will effect the ignition of the solid fuel suspension. Thereafter, the suspension, if proper air-to-fuel ratio is maintained, will continue to burn due to the high temperatures in the furnace. However, the flame thus produced may, by reason of delayed combustion, be rather long so that it may still be desirable to use a small quantity of liquid or gaseous fuel to insure complete combustion in a small space and with a quite short flame. This last is, in general, not a problem which arises when the fuel is adequately ground and sufficient air is provided for combustion. In fact tests have shown that anthracite may be ground in accordance with the invention to such fineness that 40% is less than one micron in size (theoretical 12,500 mesh). In such case the flame may be very short

fuels, including coal, there will be an additional very important type of disintegration occurring due to the great drop of pressure through the nozzles occurring with great rapidity so that the internal expansion of fluid in the pores will effect explosive disintegration. The disintegration thus occasioned, however, will solely occur in materials of porous nature and will not occur in general in the rock material which is relatively non-porous. As a result of this action, there is a 10 selective degree of grinding or comminution which occurs; i. e., the carbonaceous porous fuel will be reduced to very fine particles as compared with the rock or other adulterating material. Consequently, it is possible to effect separation of the 15 two materials so that what passes to the point of combustion will contain a higher proportion of carbonaceous fuel than the original material fed to the mill.

The separation is effected by associating the region 126 into which the nozzles discharge with a separator of cyclone type indicated as comprising a cylindrical section 128 axially communicating with the region 126, a conical section 130 forming a continuation of the cylinder 128, and a receiver conventionalized at 132. The high rate of rotation induced by the jets from the nozzles 124 will serve to effect centrifugal separation so that the relatively larger particles will be centrifugally thrown outwardly in the separator and will drop into the receiver 132. On the other hand, the finest particles will be carried by the issuing fluid through the opening 136 of the outlet passage 134, which opening 136 projects downwardly into the separator region as indicated. From 134, the suspension of fuel in the elastic fluid will pass to the combustion point as in the previous modification.

It will be evident, therefore, that by a suitable selection of the amount of elastic fluid introduced into the nozzles 100, there may be avoided the ultra-fine grinding of contaminating incombustible material, with the result that a very low grade fuel containing quite large proportions of rock may be transformed into a relatively high grade fuel passing to the point of combustion. While inevitably some of the rock or the like will be ground to a sufficiently fine degree to pass with the fuel, not only will the proportion of this be less than the proportion of rock in the original material, but the particles thereof will be so fine as to pass out with the flue gases along with the fine ash which may result from the combustion of the fuel itself. Thus, the accumulation of rock in the combustion chamber will be greatly reduced over what would occur if a corresponding economy of grinding were effected in the modification of Figure 1. With the same fuel in the modification of Figure 1, the grinding would have to be carried out to an extent insuring that all of the contaminating material was reduced to a very fine state of subdivision along with the fuel.

To secure effective explosive action in the fuel particles, the temperature and pressure conditions in the first stage should be desirably such as to maintain water in liquid form in the particles; i. e., the temperature should be below the boiling point of water at the existing pressure. Under such conditions, the dropping of pressure in the second stage results in an enormous increase in volume as the liquid water turns into steam, this taking place in the very short period of time of passage through the nozzles 124, with resulting great violence in explosive action. The

above requirement will indicate that the steam existing in the region 112 should be saturated or wet rather than superheated.

It will be noted that wet, as well as dry, fuel may be satisfactorily handled in accordance with the invention, since actual drops of water will be disintegrated, if not vaporized, and will not impede in any way the burning action.

The fuel particle sizes achieved with the types of apparatus indicated are not critical, and adjustments may be readily made to secure ranges of particles of quite different sizes. However, as compared with mechanical grinding of coal or the like, the particles will, in general, be quite small, average sizes of around 25 microns being readily secured without uneconomical use of grinding fluid. The attainment of much smaller particles of the order of a few microns in size necessarily involves the use of greater numbers of jets for effecting grinding and the particle sizes involved depend, therefore, upon the questions of cost, considered in connection with the advantages resulting from small size particles. If the fuel is of high grade, i. e., low ash content, even relatively large size particles will give rise to ash having very small particle sizes and, consequently, subject to very wide distribution from a stack. In general, ash particles of as large size as 20 microns are tolerable from the standpoint of dispersion over a large area from a stack. Under some conditions, however, where the fuel is to be used to provide the gases for combustion engines or gas turbines, it is desirable that the ash particles be very small. This result is directly related to the fine grinding of the fuel itself and with an ordinary average grade fuel, a grinding of the fuel to particles of the order of less than 20 microns will result in the production of ash particles of extremely small sizes.

What I claim is:

1. The method of effecting separation of solid materials, one of which is capable of disintegration by sudden pressure drop and another of which is not so disintegrated, comprising the steps of producing a suspension of said materials in a fine powder in an elastic fluid at high pressure, suddenly lowering the pressure of said suspension, and then subjecting the suspension after the pressure drop to centrifugal separating action to separate the material disintegrated by the pressure drop from material not so disintegrated, the separation excluding the disintegrated material from recirculation through the pressure drop step.

2. The method of effecting separation of solid materials, one of which is capable of disintegration by sudden pressure drop and another of which is not so disintegrated, comprising the steps of producing a suspension of said materials in a fine powder in an elastic fluid at high pressure, suddenly lowering the pressure of said suspension by passing said suspension through a nozzle, and then subjecting the suspension after the pressure drop to centrifugal separating action to separate the material disintegrated by the pressure drop from material not so disintegrated, the separation excluding the disintegrated material from recirculation through the pressure drop step.

3. The method of effecting separation of solid materials, one of which is capable of disintegration by sudden pressure drop and another of which is not so disintegrated, comprising the steps of producing a suspension of said materials in a fine powder in an elastic fluid at high pressure by subjecting the materials to the grinding action

and combustion may be carried out in chambers originally designed for burning oil.

The apparatus so far described is applicable to high grade fuels, i. e., those containing only small quantities of unburnable mineral matter, as well as relatively low grade fuels if in the latter case the grinding is effected to reduce the particle sizes to such an extent that all unburned solid material is readily carried from the combustion zone in the flue gases. In the case of low grade coals, for example, there may occur actual particles of rock, such as slate or sand, or other materials which unless reduced to a fine state would tend to accumulate in the combustion chamber. With the apparatus of Figure 1, the grinding may, by being carried out to a sufficient degree, serve to reduce all of the material entering the furnace to such a fine state of subdivision that the particles of incombustible material will be carried out with the flue gases. It may be noted that in general no difficulty will be encountered by ash to the extent that the ash represents the unburnable material substantially molecularly associated with the combustible material, since the particles of ash of this type will, after the combustion occurs, be in general much smaller than the particles of the fuel.

In certain cases, however, the amount of foreign mineral matter in the original fuel may be so great that an excessive expenditure of energy would be required to insure the reduction of all of the material to particles of sufficient fineness. Generally speaking, taking coal as an example, the coal is rather easily ground in a mill of the type described, whereas rock particles with which it is associated and which may, in some cases, form rather large aggregates may be relatively difficult to grind from the standpoint of time involved. Under such conditions it may be undesirable to carry out the grinding to a sufficient extent to achieve the necessary fineness of the rock material. It is, therefore, within the contemplation of the invention to effect the disintegration of the fuel in such fashion as to achieve what is, in a sense, a selective grinding operation whereby the fuel is reduced to very fine particles but the foreign material may be reduced to a substantially less extent and may be separable from the fine particles of fuel which alone may pass to a burner or other use. To achieve this end, use is made of the fact that if an organic material such as coal which is of porous nature, is subjected to a rapid pressure drop from a high pressure to a relatively low one, it will be disintegrated by internal explosion resulting in part from the sudden expansion of elastic fluid in its pores forced thereinto by its original subjection to high pressure or by the explosive vaporization of liquid such as water in its pores as the pressure is reduced when it is subjected to a temperature in excess of the boiling point of the liquid. Carbonaceous fuels in general contain water which can be evaporated in ordinary subjection to temperatures above the boiling point and so-called "inherent" water which is not ordinarily evaporable but which in this process contributes to the disintegration. As will be evident, the precise mechanism of this internal explosion is immaterial, it being sufficient to say that, in fact, the particles are disintegrated by interior expansion of elastic fluid when they are subjected to a substantial and rapid pressure drop.

The apparatus of Figures 5, 6, and 7 is adapted to the carrying out of this procedure. A grinding mill comprises a tubular lower turn 98 in

which grinding is effected, as in the mills of the patents referred to above, by the action of high velocity elastic fluid jets issuing from nozzles 100 which are fed with steam or air under high pressure from a supply connection 102. In the present case, the pressure involved in the feed should be quite high and the nozzles 100 should be of abrupt type serving to expand the elastic fluid through a pressure drop to achieve high velocity jets with, however, the maintenance of pressure in the jets at a quite high value, the pressure in the mill being maintained by proper restriction of its outlet with respect to the rate of supply of the elastic fluid. Since there exists in the mill a quite high pressure as compared with the pressure in the mill of Figure 1, which may be very little above atmospheric pressure, the material supply must also be under the high pressure, and this is represented diagrammatically by the provision of a closed hopper 104 subjected to the pressure in the line 102 through the connection 106, feed of the material being effected through a screw conveyor arrangement 108 driven by a motor 110. The hopper 104 will, of course, be of very substantial size to hold large quantities of fuel, and the showing in Figure 5 is purely diagrammatic with respect to size. It may be automatically supplied with fuel without drop of pressure therein through a suitable rotating valve arrangement of conventional type.

The material from the grinding zone 98 passes through the upwardly arranged stack 112 and through a nozzle section 114 substantially tangentially to a wall 116 at the upper part of the mill, whence it may return through a passage 118 to the grinding zone. The upper part of the mill has a form which will be clear from Figure 6, comprising an annular passage 120 communicating with the region adjacent the wall 116 and bounded inwardly by a cylindrical wall 122. As will be evident from Figure 6, the increase of velocity occasioned by the presence of the nozzle 114 will serve to accelerate the particles of the material being ground to such high velocities that large particles will pass directly into the downwardly directed passage 118 without entering the annular passage 120, thereby to be recirculated through the grinding zone for further reduction. The jet issuing from the nozzle 114 will, by virtue of its tangential relationship to the annular passage 120, induce circulatory flow through the passage 120 in the direction of the arrow. During such circulation, particles of intermediate sizes which may have been carried thereinto by the fluid will be centrifugally thrown outwardly and on the next time around will be thrown toward the wall 116 to enter the passage 118, thereby being returned to the grinding zone. Only the smallest particles, therefore, will pass adjacent the wall 122 to pass through nozzles 124 therein to the interior region 126.

The nozzles 124, as will be clear from Figure 7, are of the converging-diverging type (De Laval type), serving to expand the elastic fluid from the relatively high pressure existing in the mill to a pressure which may be little in excess of atmospheric pressure existing in the region 126. As a result, jets of very high velocity substantially exceeding acoustic velocity will be produced in the region 126. These jets intersecting as indicated by the construction lines will create intense turbulence and impact in the region 126, serving to effect further grinding of the particles circulating about this region. In the case of porous materials, however, such as most solid

of at least one high velocity elastic fluid jet, suddenly lowering the pressure of said suspension, and then subjecting the suspension after the pressure drop to centrifugal separating action to separate the material disintegrated by the pressure drop from material not so disintegrated, the separation excluding the disintegrated material from recirculation through the pressure drop step.

4. The method of effecting separation of solid materials, one of which is capable of disintegration by sudden pressure drop and another of which is not so disintegrated, comprising the steps of producing a suspension of said materials in a fine powder in an elastic fluid at high pressure by subjecting the materials to the grinding action of at least one high velocity elastic fluid jet, suddenly lowering the pressure of said suspension by passing said suspension through a nozzle, and then subjecting the suspension after the pressure drop to centrifugal separating action to separate the material disintegrated by the pressure drop from material not so disintegrated, the separation excluding the disintegrated material from recirculation through the pressure drop step.
